STEAM LAUNDRY AND PRESSING IRON

Thomas Stockton, Detroit, Mich.

Application April 25, 1934, Serial No. 722,390

3 Claims. (Cl. 38—77)

The invention relates to laundry and pressing irons of that type which during operation constantly discharge steam through ports in the ironing or pressing surface into the fabric being pressed. It is the object of the invention to obtain a construction in which the steam is internally generated but is limited in pressure by the pressure of a water supply connection. It is a further object to automatically control the heat of the iron so as to always maintain the ports and passages through which the steam passes at a temperature above the boiling point of water, thereby avoiding any danger of unvaporized water coming in contact with the fabric and at the same time to avoid any abnormal rise in temperature within the body of the iron. Still further it is an object to provide means by which the operator can control the amount of steam generated according to the requirements of the work. With these objects in view the invention consists in the construction as hereinafter set forth.

In the drawing:

Fig. 1 is a vertical longitudinal section through an electrically heated steam iron of my improved construction, the section being substantially on line 2—2, Fig. 2;

Fig. 2 is a plan view of the base of the iron with the cover and handle removed therefrom;

Fig. 3 is a bottom plan view showing the arrangement of steam ports in the ironing face;

Fig. 4 is a cross section on line 4—4 of Fig. 2;

Fig. 5 is a section on line 5—5, Fig. 2;

Fig. 6 is a cross section on line 6—6, Fig. 1.

The body of my improved iron is preferably formed of material having relatively high thermal conductivity, such for instance as an aluminum alloy. This body A has formed centrally and longitudinally thereof chambers B and C and upon opposite sides of these chambers are arranged sections of an electrical heating unit D. This unit is preferably of the armored type and is preferably cast into the body so as to be in close thermal conductive relation thereto. The chambers B and C are closed by a cover plate E secured to the body A by bolts and provided with upwardly extending screw threaded studs G. H is a hood or cover plate through which the studs G pass and I are nuts engaging the studs for clamping the cover plate and a handle J to the body A.

At the rear and at one side of the body A is a tubular post K through which water is introduced for the generation of the steam. From this tubular post a passage K' extends downward into the body A and is connected by a longitudinally ex-

tending passage K² to the chamber B. Above the passage K² the body A is recessed to receive a thermostat L which automatically controls the temperature of the iron. Inasmuch, however, as the water passage K² is between the electrical heating unit D and the thermostat, the latter will instantaneously respond to any cooling effect of incoming water to supply additional heat for converting the same into steam. Between the chambers B and C is a partition B' which extends upward into proximity to the cover plate E, leaving only a restricted clearance for passage of steam. The chamber B is also preferably provided with a horizontal baffle plate B² which separates the lower portion of this chamber from an upper portion of restricted depth and which communicates with the chamber C. The chamber C is connected with a vertical passage C' extending downward between the sections of the heating unit D and connecting with a transverse passage C² below said unit. The opposite ends of the passage C² are connected with longitudinally extending passages M and M' which are substantially parallel to the sides of the body A and have connected thereto a series of ports N discharging through the ironing face. Thus any steam generated in the chamber B will pass over the baffle B² into the chamber C down through the passage C' and lateral passage C² to the longitudinal passages M and M' and will finally be discharged through the ports N.

The hollow post K has connected to its upper end a valve casing O provided with a rearwardly extending nipple O' connected to a flexible tube P leading from a source of water supply. Connecting with the nipple O' is a passage O² which may be variably restricted by means of an adjustable threaded stem Q having an actuating head Q' at its upper end. The passage O² leads to a chamber O³ containing a valve stem R having a valve R' controlling said passage. From the chamber O³ a passage O⁴ leads to the hollow post K. The valve stem R has a threaded engagement with a plug R² closing the end of the chamber O³, and the outer end of said stem has a rock arm T extending upward and having a thumb piece T' at its upper end adjacent to the handle J. Thus the operator can manipulate the rock arm T by the hand which grasps the handle to either open or close the valve R'. However, when the valve is closed against its seat, there is still an opening for the feeding of a minute quantity of water formed by a narrow channel R³ in the face of the valve. Also, to prevent any leakage of water from the chamber O³ around the

valve stem R, a packing R⁴ is placed around the valve and is held tight by the tension of a spring S.

Electrical current is supplied to the iron 5 through a suitable cord U and conductors V within the hood connect the thermostat and the heating unit D in series.

In use, when the iron is connected by the cord U with an electrical service and by the tube P 10 with a water supply under pressure, the body A of the iron will be heated to a temperature above the boiling point of water but overheating will be prevented by the thermostat L. The stem Q is adjusted in accordance with the pressure on 15 the water supply line so as to permit only a restricted flow of water from the tube P into the chamber O³. Flow from this chamber into the hollow post K and thence into the chamber B is controlled by the valve R which when seated per- 20 mits a very restricted amount of water to pass through the channel R³. Thus assuming that the body A has been preheated, the water passing to the chamber B will flash into steam and when the steam pressure balances the water pres- 25 sure, further flow of water to said chamber will be arrested. While work is being performed, the operator can variably increase the generation of steam by pressing against the thumb piece T' of the lever T which by opening the valve R' will 30 permit a greater flow of water into the chamber B. However, as before stated, the pressure in this chamber can never rise to a greater height than the pressure on the water line, as this will result in driving back water from said chamber. 35 Some of the important features of the invention are—

First, that the temperature of the body A in which the steam passages are formed is always maintained above the boiling point of water so that under no circumstances can unvaporized water be discharged through the ports N:

Second, the pressure of steam in the chambers and passages within the iron is limited to the pressure of the water system;

Third, a constant flow of a restricted quantity of water is permitted so as to maintain steam, even when the iron is not in actual use, this also to prevent overheating of the valve casing O;

Fourth, the passage of the water into the body 50 of the iron in close proximity to the thermostat insures that heat will always be generated when any water is flowing but will be cut off when the steam pressure equals the water pressure and the temperature of the body exceeds a predetermined point;

Fifth, the casting of the electrical heat unit into the body of the iron insures high thermal conductivity and a uniform temperature in all portions of the ironing or pressing surface;

Sixth, the quantity of steam generated may be varied by the operation of the lever T which is controlled by the hand used in manipulating the iron.

Seventh, a very vital feature of the construction is that the steam generated in the chamber B must pass various baffles and restrictions before it finally finds access to the channels M and M' having the ports leading to the ironing face. As all of the parts are heated to a temperature 70 above the boiling point of water, it is evident that any mist or water particles carried in suspension will be eliminated before the steam finds access to the ports N so that there is no possibility of injuring the garment by water coming in contact 75 therewith.

Eighth, the variable restriction to the water flow formed by the adjustable stem Q permits of so adjusting that the admission of water to the steam generating chamber is always within the steam producing capacity of the electrical heating means as controlled by the thermostat. In other words, the incoming water can never exceed the capacity of the iron for converting the same into steam so that under no circumstances can water pass through and be discharged from the ports. 10

Ninth, provision is made for removing scale which might otherwise clog the iron and prevent its operation. As the water supply always contains a certain amount of mineral matter in solution, this will be deposited at the point where the water is first converted into steam. Thus with the construction shown, the passage K² which extends from the hollow post to the steam chamber intermediate the thermostat and the electrical heater is particularly subject to deposits. I have therefore provided means for cleaning out this passage comprising a removable screw threaded plug U which closes an opening into the passage K² from the side of the iron. This permits of the insertion of any suitable cleaning tool to scrape off any deposits that may occur in this passage. It is also possible to clean out the chamber B, should any deposits occur therein by removing the cover plate E. 15 20 25 30

Tenth, the steam generating chamber B has a port B³ (Figure 5) of fairly restricted area through which the steam from said chamber must pass above the baffle plate B². This imparts considerable velocity to the current of steam with a 35 sudden change in direction, with the effect that mist particles are thrown out of the current against the hot surface of the cover member E. The effect is repeated by other restrictions at various points in the steam passage before reaching the ports N. 40

What I claim as my invention is:

1. A steam laundry and pressing iron comprising a one-piece body having an ironing face, a steam generating chamber above said face and having a water inlet, and steam passages leading from said chamber through said body to the ironing face, an electrical heater embedded in said one-piece body adjacent said chamber and steam passages, and a thermostat also within said body adjacent said water inlet so as to be influenced by the presence or absence of water in said inlet for controlling said heater to maintain all portions of said body through which the steam passes at a predetermined temperature above the 55 boiling point of water.

2. A steam laundry and pressing iron comprising a one-piece body having an ironing face, a steam generating chamber above said face, steam passages leading from said chamber through said body to the ironing face and provided with ports opening through said face, an electrical heater embedded in said one-piece body adjacent said chamber and steam passages, a thermostat also within said body adjacent said chamber controlling said heater to maintain all portions of said body through which the steam passes at a predetermined temperature above the 60 boiling point of water, and a conduit connected to said iron and leading from a source of water supply under pressure, said body having a passage from said conduit to said steam generating chamber extending in such proximity to the thermostat that the thermostat will be in- 65 70 75

fluenced by the presence or absence of incoming water in said passage.

3. In a steam laundry and pressing iron, a body having an ironing face, a steam generating chamber above said face, steam ports opening through the ironing face, and a passage intermediate said generating chamber and ports, an electrical heater within the body for maintaining the same and all portions thereof in contact with the steam

at a temperature above the boiling point of water, a thermostat within the body controlling said heater, and means for feeding water under pressure from an external source to said steam generating chamber, including a passage intermediate said thermostat and heater in which water is first heated and partially vaporized.

THOMAS STOCKTON.
